UNITED STATES PATENT OFFICE

96,779

DESIGN FOR A BOTTLE

Morris Sanders, Jr., New York, N. Y., assignor to Schenley Products Company, New York, N. Y., a corporation of New Jersey

Application July 12, 1935, Serial No. 57,611

Term of patent 14 years

To all whom it may concern:

Be it known that I, Morris Sanders, Jr., a citizen of the United States, residing at 20 West 40th Street, New York, county of New York, and State of New York, have invented a new, original, and ornamental Design of a Bottle, of which the following is a specification, reference being had to the accompanying drawing, forming a part thereof.

I claim:

The ornamental design for a bottle as shown.

MORRIS SANDERS, JR.
